UNITED STATES PATENT OFFICE.

WILLIAM C. McKEOWN, OF BUFFALO, NEW YORK, ASSIGNOR TO UNITED STATES INCINERATOR COMPANY, OF BUFFALO, NEW YORK, A CORPORATION OF NEW YORK.

INCINERATOR.

1,140,472.

Specification of Letters Patent. Patented May 25, 1915.

Application filed July 15, 1911. Serial No. 638,723.

To all whom it may concern:

Be it known that I, WILLIAM C. McKEOWN, a citizen of the United States, residing at Buffalo, in the county of Erie and State 5 of New York, have invented new and useful Improvements in Incinerators, of which the following is a specification.

My invention relates to improvements in incinerators for the disposal of garbage, 10 excrement, and other matter, and it has for its primary object the provision of an incinerator formed of units or sections so that it may be constructed in different sizes by assembling different numbers of units or 15 sections, and so that when constructed it may be enlarged or diminished in length, as may be found desirable or necessary.

Another object of my invention is the production of a simple, inexpensive, and effective incinerator in which comparatively few 20 parts are employed and in which both solid and fluid or liquid matter may be quickly reduced and consumed.

With these and other objects in view to 25 appear hereinafter, my invention consists in the construction, arrangement and combination of parts to be hereinafter described and particularly pointed out in the subjoined claims.

30 In the drawings, Figure 1 is a side elevation of an incinerator embodying my invention in a representative form. Fig. 2 is a front elevation of the same. Fig. 3 is a rear elevation. Fig. 4 is a central longitudinal section, on a slightly enlarged scale. Fig. 5 is a horizontal section on a slightly 35 enlarged scale, taken on line $w-w$, Fig. 1. Fig. 6 is a transverse section taken on line $x-x$, Fig. 1. Fig. 7 is a transverse section 40 on a slightly enlarged scale, taken on line $y-y$, Fig. 1. Fig. 8 is a plan view of one of the closure plates and its coöperating kettle. Fig. 9 is a transverse section taken on line 45 $z-z$, Fig. 8. Fig. 10 is a plan view of one of the closure plates.

Referring now to the drawings in detail, corresponding numerals of reference refer to corresponding parts in the several figures.

The reference numeral 8 designates the 50 casing consisting of a plurality of sections 9 connected together in an operative manner so that they may be disassembled and one or more sections dispensed with, or additional sections added thereto, as may be 55 found desirable or necessary. Each section

forms a unit adapted for use with another or any other number of units, to form a complete incinerator.

The casing may be constructed of cast-iron, sheet metal, or any other suitable material, but by preference and as herein shown and described, it is made of cast iron; each unit or section comprising two spaced side members 10 and a top plate 11 and each side member comprising two parts 12, 13, one 60 surmounting the other. The lower part of each side member serves as a leg or support while the upper part is made hollow and with the other corresponding upper parts serves as an air channel, designated by the 65 numeral 14. The side members are therefore arranged in two spaced sets, the members of each set being in alinement. Each lower part or leg is connected with the adjoining leg or legs, by means of bolts 15 and 70 the upper or channel parts of each set are connected together by a bolt 16 extending from one end of the casing to the other. The space 80 between the two sets of side members is closed at the top by the top- 75 plates 11, each of which is preferably inclined laterally in opposite directions from its medial point and in each inclined portion is an opening 17 over or around which is fitted a closet seat 18. Fitted onto each closet 80 seat is a cover 19 to close the opening in the closet seat and the opening in the top plate directly beneath. The covers 19 may be hinged or otherwise secured so that the 85 openings in the seats 18 are exposed, and the seat may also be hinged or otherwise applied so that they may be raised or removed from the top plates, as may be desired.

The front of the casing is closed with a plate 20 conforming in shape to the cross-sectional shape of the units or sections and closing the front ends of the channels 14 and the space 80 between the side members 10. This plate is secured in place by means of the bolts 16 and also by means of bolts 90 95 100 105 110 passed through the forward lower parts or legs 13. The rear of the casing is also closed with a plate 21 of similar shape serving to close the rear end of said space, but having openings 22 which register with the channels 14, for a purpose to hereinafter appear. This plate is also held in position by means of the bolts 16 and bolts 82 that are passed through the rear lower parts or legs 13.

The lower parts or legs of each side member have ledges 23 projecting inward from their inner surfaces on which are supported the grate sections 24, the liquid capacity tank 25, and the liquid evaporating tanks 26.

In the embodiment of my invention herein disclosed, four units or sections are shown, and the grate and liquid evaporating tanks which lie at opposite sides of the 10 grate extend from the front end of the casing to the rear end of the second unit or section, while the liquid capacity tank extends from the front end of the third unit or section to the rear end of the casing. The 15 liquid evaporating tanks are removable from the casing through openings 27 in the front plate and are flanged, as at 28, to limit the extent to which they are inserted into the casing. By means of bolts or screws passed 20 through the flanges 28 and taking into the front plate 20 said evaporating tanks are held securely in place and as they are positioned at opposite sides of the grate they form the sides of the fire box 29. The liquid 25 capacity tank spans the space 80 and receives support at its longitudinal marginal portions from the ledges 23. It is positioned directly in rear of the grate and the liquid evaporating tanks and serves as a bridge 30 wall for the furnace portion of the incinerator.

Arranged in a plane between the top of the casing and the liquid capacity tank and grate, are rectangular closure plates 30, one 35 plate being provided for each unit or section. Each plate has an opening 31 in which, under normal conditions, fits the upper end of a kettle 32, in which is to be deposited garbage, excrement, or other matter 40 to be disposed of. With the kettles 32 in position a space 33 is provided above the same and the plates 30 and a space 34 is also provided between the plates 30 and the capacity tank and grate. The kettles 32 extend 45 into the space 34 and are pivotally mounted so they may be turned and the contents discharged into the fire and onto the capacity tank to be removed from the latter by drawing the matter forward into the fire by means of a suitable implement inserted through the fuel opening 35 in the front plate, which opening may be closed 50 by a door 36. Said fuel opening extends beneath the plane in which the grate is held 55 so that access can be had therethrough to the ash pit 37 beneath the grate.

Underneath the liquid capacity tank 25 is a space 38 which is practically a continuation of the ash-pit and serves as an air passage 60 in communication with vertical air-flues 39 secured to the back plate of the casing through openings 40 in said plate. The upper ends of said air flues are in communication with the space 33 above the kettles 65 through openings 41 in said back-plate and

said space 33 is in communication at its front end with the channels 14 in the side members of the casing through openings 42.

Secured to the back plate of the casing is a smoke-box 43 having a smoke pipe 44 70 attached thereto and by means of openings 45, 46 in said back-plate, said smoke box is in communication, respectively, with the spaces 33 and 34. The opening 45 located in the back plate between the smoke-box 75 and the space 33 has a damper or valve 47 to which is applied a rod 48 leading to the front of the incinerator to permit of easily manipulating the damper while attending to the fire. 80

At the rear end of the incinerator a urine or liquid receiving tank 49 is located which partly surrounds the smoke box and has two flues 50 extending upward therefrom which are in communication with the passages 14 85 in the side members through the openings 22 in the back plate. Said liquid receiving tank has a number of openings 51 in its top wall, closed or adapted to be closed by lids 52 hinged to said wall so that the openings 90 may be closed when the tank is not in use. Said tank has also an opening 53 in its rear wall for admission of air into the tank at all times. The bottom of the tank preferably slopes to a common point, at which a 95 discharge pipe 54 is secured which leads the liquid into the liquid capacity tank, as at 55, and in order to prevent clogging of said pipe, a screen 56 is placed in the liquid receiving tank a distance above its bottom. A 100 screen 57 is also fitted to the opening 53 to prevent the mischievous insertion into the tank 49 of solid or other matter likely to clog the discharge pipe 54.

Each of the closure plates 30 comprises 105 a plate portion 58 having the opening 31 therein conforming or approximately conforming to the contour of the kettle to provide a space 84 between the two, the space 110 at one side of the kettle being somewhat larger than at the other side thereof so as to form shoulders 85 at opposite points. Each closure plate has a marginal flange 59 through which bolts, screws, or other fastening means are passed that take into or pass 115 through the inner walls of the side members to securely fasten the plates in place. Adjoining closure plates abut against each other and the front and rear plates 21, 22, respectively, of the casing. The kettles are 120 so arranged in the closure plates that they may be turned or rocked therein to dump the contents and so that when in normal position, they effectually close all communication 125 between the spaces 33, 34. For this purpose each kettle has two flanges 60, 61 arranged in different horizontal planes so that when one lies against the under side of its coöperating closure plate 30, the other lies against the upper side thereof, as best 130

shown in Figs. 4, 7 and 9. The flange of each kettle bearing against the upper side of the closure plate is somewhat narrower than the flange bearing against the under side thereof and serves to close the narrow portion of the space 84 between the kettle and the closure plate while the flange bearing against the under side of said closure plate serves to close the wider portion 10 of the space between the kettle and said plate, as best shown in Fig. 8.

Each kettle has a pair of hollow trunnions or pivots 62 arranged preferably in a plane beneath the flanges 60, 61, each of said trunnions being journaled or supported in a U-shaped bearing 63 which opens into a vertical liquid duct 64 cast within the upper part of the coöperating side member and having a lateral extension 65 at its upper end opening through the outer wall of said side member and arranged in line with the hollow trunnion or pivot so that access may be had to the same and to said vertical liquid duct for cleaning them in the event 25 of their becoming clogged and also to permit the insertion of a suitable tool into the hollow trunnion, which is made square interiorly so that the kettle may be turned or rocked.

30 The vertical liquid ducts 64 at each side of the casing are connected by a pipe 66 which leads to the liquid capacity tank, as at 67, so that any liquid matter deposited from necessity or otherwise into the kettles 35 may overflow into the vertical liquid ducts when the level is above the lowest points of the bores of the trunnions or pivots, and from there be delivered into the capacity tank by the pipes 66 at opposite sides of the 40 incinerator. The lateral extensions 65 of the liquid ducts are closed by screw-plugs 68 or otherwise so that there can be no escape of liquid matter therethrough. One of the flanges of the kettle extends from one side 45 thereof and terminates at points beyond the plane in which the pivots of the kettle are arranged while the other flange extends from the other side of the kettle and terminates at points in line with or substantially 50 in line with the extremities of the first mentioned flange, said flanges terminating also in line with the shoulders in the openings 31. The extremities of the flanges are beveled, as at 75, so that the closure plate may be 55 swung on the kettle and drawn to one side for removing the same, the enlarged portion of the opening 31 permitting the narrow flange 60 to pass therethrough.

The liquid capacity tank is connected with 60 both liquid evaporating tanks by means of pipes 69, in each of which is a union 70 to permit of conveniently disconnecting the evaporating tanks and the capacity tank. Each of the liquid evaporating tanks and 65 the capacity tank have overflow pipes 71

fastened into the bottoms of the tanks and extending up within short distances of their tops. The overflow pipes in the evaporating tanks are particularly desirable owing to the tendency of urine to foam and boil 70 over when heated.

The use and operation of the apparatus is as follows:—The kettles 32 are used to receive solid matter, such as excrement and garbage, while the liquid receiving tank 49 75 is for the reception of urine or other liquids, which is led from said tank to the liquid capacity tank 25 and from the latter to the liquid evaporating tanks 26 which are subjected to the heat of the fire in the fire box. 80

During the accumulation of the solid matter, the damper 47 in or for the opening 45 in the back-plate is open so that the foul odors from the accumulated matter may escape through the smoke stack, which rises to 85 a sufficient height to create the necessary draft and direct the odors to a region beyond detection.

When the contents of the kettle contain liquid matter, such matter may overflow 90 through the hollow trunnions or pivots 62 and pass into the liquid capacity tank and from said capacity tank into the liquid evaporating tanks, and as the connection of the capacity tank to each evaporating tank 95 is near their bottoms, the liquid in both is maintained on a level. When the kettles contain sufficient matter, a fire is built in the fire box, and at such times the damper 47 is closed so that the odors and gases from the 100 solid matter and also those from the liquid matter escaping through the overflow pipes 71 in the evaporating tanks, are drawn through the fire and thereby consumed.

The outer air is drawn into the liquid 105 receiving tank 49 through the opening 53, thence through the flues 50 to the passages 14, from the latter through the openings 42 in the side members of the foremost or first section to the space 33 above the kettles where it mingles with the gases and odors of the accumulated solid matter. From the space 33 the gases and odors are drawn into the air flues 39, thence through the openings 40 to the space 38 and ash-pit 110 37, and finally through the grate and fire to be consumed. The products of combustion pass through the space 34 underneath and around the kettles 32, then through the opening 46 into and out the smoke pipe. 115 During such action incineration of the matter in the kettles takes place and the liquid matter in the evaporating tanks is also consumed, and at such times the closet seats 18 and covers 19 are elevated or removed and 120 metal plates fitted over the openings 17.

When the solid matter in the kettles is incinerated, the kettles are turned or rocked on their pivots to dump the ash therein onto the fire and the liquid capacity tank, from 130

which latter it may be drawn forward onto the fire.

When decreasing the number of units or sections, a smaller fire place or a smaller capacity tank may be used, or both a smaller fire place and capacity tank, and when increasing the number of units or sections a larger fire place or a larger capacity tank may be used, or both a larger fire place and capacity tank, as may be found desirable or necessary.

It is apparent that minor changes in construction and arrangement of parts may be resorted to without departing from my invention or sacrificing any of the advantages thereof.

Having thus described my invention, what I claim is,—

1. In an incinerator, a casing formed of 20 a plurality of connected units or sections, each comprising spaced side members, a top plate having an opening, a back plate and a front plate closing the space separating said side members, the connected side members at each side of the casing having a passage therethrough and one of said units or sections having an opening connecting said passage with the space between opposite side members, a liquid receiving tank in communication with the passages in said side members, a fire box within said casing, a kettle pivotally-mounted within each unit or section, said kettles being separated from said top plates by an intervening space, 30 flues connecting said intervening space with the fire box from beneath, a smoke pipe in communication with said fire box and with the space between said kettles and top plates, and means for closing communication 40 with said last-mentioned space and said smoke pipe.

2. An incinerator comprising a casing having a plurality of kettles, a fire box in a plane beneath said kettles, a liquid capacity tank in rear of said fire box serving as a bridge wall, and evaporating tanks at opposite sides of said fire box and in connection with said capacity tank.

3. An incinerator comprising a casing 50 having a plurality of kettles with spaces above and beneath the same, a fire box in a plane beneath said kettles, a smoke pipe for said casing in communication with the spaces above and beneath said kettles, means for closing communication between said smoke pipe and the space above said kettles, a liquid-receiving tank in communication with the space above said kettles and having a discharge pipe attached thereto, a liquid evaporating tank in operative relation to said fire box and having communication with said discharge pipe, means of communication between the space above said kettles and said fire box, and an overflow pipe common to said kettles and in com-

munication with said liquid evaporating tank.

4. An incinerator comprising a casing, a plurality of kettles within said casing having spaces above and beneath the same and being provided with hollow pivots, a smoke pipe in communication with the spaces above and below said kettles, a fire box in a plane beneath said kettles, and a liquid evaporating tank having communication 75 with the hollow pivots of said kettles.

5. An incinerator comprising a casing having side members separated by an intervening space, a top plate closing the top of said space, a back plate closing the rear end of said space and a front plate closing the forward end of said space and having an opening therein, said side members having inwardly directed ledges, a fire grate supported by said ledges, a kettle in a plane above said grate, and a liquid evaporating tank inserted through the opening of said front plate and resting upon one of said inwardly-directed ledges, said liquid evaporating tank being in communication with said 80 kettle to receive the liquid overflow therefrom.

6. An incinerator comprising a casing having a plurality of kettles, a fire box in a plane beneath said kettles, a liquid capacity 95 tank in rear of said fire box serving as a bridge wall, evaporating tanks at opposite sides of said fire box and in connection with said liquid capacity tank, and a liquid receiving tank in connection with said liquid 100 capacity tank.

7. An incinerator comprising a casing having a fire box, a plurality of kettles in a plane above said fire box, a liquid receiving tank outside of said casing, a liquid capacity tank within said casing in connection with said liquid receiving tank and having an overflow extending upward from its bottom, and a liquid evaporating tank in connection with said liquid capacity tank 105 and having an overflow extending upward from its bottom, said liquid evaporating tank being arranged in operative relation to said fire box and being connected with said liquid capacity tank.

8. In an incinerator, a casing having hollow side members provided with inwardly extending U-shaped bearings and liquid ducts leading from said bearings, a liquid capacity tank within said casing, a pipe 115 connecting the liquid ducts at each side of said casing with said capacity tank, kettles provided with hollow pivots journaled in said U-shaped bearings, a liquid evaporating tank in connection with said liquid capacity 120 tank, and a fire box in operative connection with said kettles and said liquid evaporating tanks.

9. An incinerator comprising a casing having a plurality of pivoted kettles, a 130

smoke pipe in communication with the spaces above and beneath said kettles, a fire box in a plane beneath said kettles, means of communication between the space above 5 said kettles and said fire box from beneath, a liquid receiving tank outside of said casing and having an air inlet and being in communication with the space above said kettles, and a liquid evaporating tank in

communication with said liquid receiving tank.

In testimony whereof, I have affixed my signature in the presence of two subscribing witnesses.

WILLIAM C. McKEOWN.
